[57] ABSTRACT

A multibreak puffer type circuit interrupter having a cylindrical metal enclosure filled with compressed gas, such as sulfur hexafluoride. Longitudinal beams extend in the enclosure to support a plurality of transverse support plates forming partition walls defining therebetween a number of sections housing the different arc-extinguishing units. The units of odd rank are aligned on a first axis and the units of even rank are aligned on a second axis, both axes being symmetrically offset from the axis of the enclosure. The exhaust ends of the units are laterally juxtaposed to the puffer mechanism of the next-following units so as to obtain an overlapping of the units permitting to reduce the overall length of the pole.

**MULTIBREAK METAL-CLAD PUFFER TYPE
CIRCUIT INTERRUPTER HAVING STAGGERED
ARC-EXTINQUISHING UNITS**

This invention relates to high-voltage metal-clad multibreak circuit interrupters and more particularly to a pole of such circuit interrupters having a plurality of electrically series-connected arc-extinguishing chambers in which an arc is drawn between a pair of separable contacts whereby a blast of compressed arc-extinguishing gas is directed to the arc in order to quench the latter.

In known circuit interrupters of this kind, the different arc-extinguishing units are housed in a metal grounded enclosure of generally cylindrical shape filled with a compressed gas having a high arc-extinguishing power and a high dielectric strength, such as sulfur hexafluoride. The high-voltage metalclad circuit interrupters of the prior art operate at dual pressure and need therefore a costly compressor station to deliver the arc-extinguishing gas at a relatively high pressure. On the other hand, the different arc-extinguishing units of a pole are aligned on a common axis so that the total length of the pole is important and increases again the cost of the installation.

It is an object of the invention to provide a single-pressure multibreak metal-clad circuit interrupter having a simple and rugged construction of reduced length and of modular design permitting to assemble circuit interrupters of different voltage ratings by simple adding of removing of standardized parts, more particularly of standardized arc-extinguishing units together with the support elements thereof.

These and other objects and advantages will become apparent upon reading of the now following description of some embodiments of the invention given by way of example only and represented in the annexed drawings, in which:

FIG. 1 is a schematic side elevational view of a pole of a circuit interrupter according to the invention, the outer casing being shown in axial cross section and the control box being shown partially broken away;

FIG. 2 is a front elevational view of the pole according to FIG. 1, the casing being again shown in cross section;

FIG. 3 is a schematic plan view wherein the top cover of the casing has been removed;

FIG. 4 is a cross sectional view on an enlarged scale of an arc extinguishing device utilized in the circuit interrupter shown in FIG. 1;

FIG. 5 shows the electric circuit diagram of an embodiment of the invention comprising auxiliary circuit opening and/or closing resistors; and

FIG. 6 is a view similar to that of FIG. 3, showing schematically the arrangement of the resistors of FIG. 5.

In the FIGS., a cylindrical metallic pressure enclosure or outer casing 10 comprises a pair of lateral cylindrical projections 12, 14 which are vertically spaced apart and support through generally cone-shaped insulators 16, 18 axial conductors 20, 22, respectively, constituting input and output connections or bushings to connect the electrically series-connected arc-extinguishing devices of the circuit interrupter to an external circuit or network. A top cover 26 and a bottom cover 24 are removably bolted to the end portions of the casing 10 in a gastight manner and the casing is

filled with a compressed gas of high arc-extinguishing and dielectric power, such as sulfur hexafluoride of, for example 3.5 bars. The cylindrical enclosure 10 shown in the FIGS. is arranged vertically but it is of course also possible to dispose the casing horizontally on a pedestal 28, the whole being in either case on earth potential.

The different elements of the multibreak pole unit located within the enclosure 10 are supported by a pair 10 of longitudinally extending beams of insulating material 30, 32 which are secured to the covers 24, 26 by bolts 34. A plurality of circular partition plates or discs of conductive material 36, 38, 40, 42, 44 are spaced apart along the beams 30, 32 and secured thereto in an appropriate manner. The end plates 36, 44 are aligned with the bushings 20, 22, respectively, and electrically connected thereto through plug-in connections 46, 48, respectively. The intermediate plates 38, 40, 42 are regularly spaced apart along the beams 30, 32 so as to 15 define four successive sections 50, 52, 54, 56, each of which corresponds to a breaking interval of the pole which comprises on the whole four breaking points, in the example shown. The distance between the plates 36 to 44 is of course adapted to the required insulation 20 level for compressed sulfur hexafluoride.

The arc-extinguishing devices which are electrically series-connected and located in the respective sections 30, 52, 54, 56 are of the puffer type and identical so that only one of them, associated with the section 56, 30 will now be described in more detail with reference to FIG. 4.

The arc-extinguishing unit comprises two distinct parts, one of which is supported by the plate 44 and associated with a stationary contact 60 while the other, 35 62, is supported by the adjacent plate 42 and associated with a movable contact 64 equipped with a puffer device having a cylinder 66 and a piston 68. The part 62 is well known so that it suffices to recall that the movable cylinder 66, which is rigidly secured to the movable contact 64, slides on the stationary piston 68, which is supported by the plate 42, so that the gas confined between the confronting wall portions of the cylinder 66 and the piston 68 can be compressed by a downward movement (with respect to FIG. 4) of the contact 64 and of the cylinder 66 in order to direct a blast of gas through the orifice 70 in the direction of the arc drawn between the separating contacts. The parts 40 58 is also well known and comprises a stationary contact 60 cooperating with a plurality of rear openings 50 72 exhausting the blast gas. The arcing contacts 64 and 60 are shown solid but may also be hollow. Preferably, main contacts 74, 76 are associated with the arcing contacts to ensure the electric continuity in closed position of the circuit interrupter. The part 58 traverses a central hole 78 of the plate 44 so as to project therefrom on both sides of the plate so that the contacts 60, 76 are arranged on one side of the plate 44 in confronting relation with the part 62, and the exhaust opening member 72 on the opposite side of the plate 44. The movable elements of the part 62 are actuated by means of a pair of control rods 80, 82 secured to the cylinder 66.

The four breaking devices are arranged in two groups, the devices of odd rank 84, 86 being essentially 65 located in the sections 50, 54, respectively, and the elements of even rank 88, 90 extending substantially within the sections 52, 56, respectively. The devices 84,

86 of odd rank are aligned on a first axis 92 (FIG. 3) which is laterally offset with respect to the axis of the cylindrical enclosure 10 and the devices 88, 90 of even rank are aligned on a second axis 94 which is also offset with respect to the axis of the cylinder, both axes 92, 94 being symmetrical with respect to the axis of the cylinder 10. The off-centering of the axes 92, 94 is sufficient to permit the juxtaposition on each intermediate plate 38, 40, 42 of a part 62 and of a part 58 pertaining to the arc-extinguishing devices 84, 88; 88, 86; and 86, 90, respectively. The staggering of the devices 84 to 90 permits an overlapping of adjacent devices and thereby a reduction of the overall length of the pole. The conducting plates 36, 38, 40, 42, 44 ensure the electrical connection between the contacts and the input and output conductors 20, 22, on the one hand, and between the movable and stationary contacts of successive arc-extinguishing devices, on the other hand. Voltage-dividing condensers 96 may advantageously be inserted between successive plates 36 to 44 in a well-known manner.

The movable contacts and the puffer mechanisms of the arc extinguishing-devices of even rank 88, 90 are mechanically actuated by the two rods 80, 82 which are in turn actuated by a control rod 98 which is directly connected thereto or indirectly through the movable elements of the arc-extinguishing device 88. The control rod 98 traverses the bottom cover 24 in a gastight manner and projects into a control box 100. Similarly, the movable elements of the arc-extinguishing devices of odd rank 84, 86 are actuated by a pair of control rods 102, 104 which are in turn actuated by a control rod 106 which extends parallelly to the control rod 98 and protrudes also, after having traversed the cover 24 in a gastight manner, into the control box 100. Thus, the control rod 98 actuates the devices 88, 90 and the control rod 106 the devices 84, 86. Each control rod 98, 106 may have an individual driving mechanism but in the embodiment shown in the FIGS., a hydraulic operating cylinder device 108 having a return spring (not shown) actuates the two control rods 98, 106 may have an individual driving mechanism but in the embodiment shown in the FIGS., a hydraulic operating cylinder device 108 having a return spring (not shown) actuates the two control rods 98, 106. In this manner, the control of the rods 98, 106 is automatically synchronized so that all the contacts of the different devices open simultaneously.

The operation of the above described circuit interrupter will be apparent. Suffice it to say that the blast gas which is compressed by the puffer mechanism in order to be directed towards the arcs between the different separating contacts is drawn from the low-pressure enclosure 10. The gas is subsequently exhausted in regions spaced relatively far away from the breaking intervals. As a result, the overlapping of the devices does not affect the insulating level of the pole.

The active parts of the pole are formed by standardized elements which permit a modular construction of a range of circuit interrupters of different ratings. Thus it is possible to provide a pole having only two arc-extinguishing units in which case only three connecting plates are necessary. With an increasing number of units only the total length of the metal enclosure 10 needs to be adapted to the overall length of the overlapping units. The inner equipment of the enclosure, comprising the insulating support beams 30, 32 and the

cross plates 36 to 44 with the arc-extinguishing units, constitutes a rigid assembly which can be withdrawn as a unit from the enclosure 10 in order to permit maintenance and exchange operations. The grounding of the metal-clad apparatus ensures the safety of the installation.

The staggering of the arc-extinguishing units between the respective cross plates lends itself particularly well to the incorporation of circuit-opening and/or -closing resistors associated with auxiliary interrupters the operation of which is suitably shifted forward or back in time with respect to the operation of the main contacts in a well-known manner. FIGS. 5 and 6 show diagrammatically an embodiment of the invention comprising resistors of the kind mentioned.

In FIG. 5, the main contacts of each unit 84, 88, 86, 90 are shunted by a series-connection of a resistor 110, 114, 118, 122 with an auxiliary interrupter 112, 116, 120, 124, respectively. Advantageously, the resistor-interrupter units 110 to 124 are staggered along two parallel axes 126, 128 visible on FIG. 6, and imbricated between the condensers 96. The coaxial auxiliary interrupters 112, 120 and 116, 124 are actuated in a manner similar to that of the main arc-extinguishing devices by a pair of auxiliary control rods (not shown) having a lowermost end portion extending within the control box 100. The central control within the control box 100 permits to obtain in a simple manner any desired sequence of the operation of the different auxiliary and main contacts. The resistor-interrupter units may all be coaxial or arranged along two or more axes.

What we claim is:

1. A multibreak arc-extinguishing pole unit for a high-voltage metal-clad puffer type circuit interrupter, comprising:

a grounded metal enclosure of substantially cylindrical shape adapted to contain a compressed arc-extinguishing gas of high dielectric strength; a plurality of electrically series-connected arc-extinguishing units spaced apart in said enclosure in the longitudinal direction thereof, each unit having a pair of elongated separable contact means extending parallelly to said longitudinal direction to draw an arc therebetween, and a puffer mechanism coaxial with said contact means and adapted to draw gas from the inside of said enclosure to direct a blast of compressed gas on said arc, said contact means comprising a relatively stationary contact and a movable contact; said puffer mechanism including relatively movable piston and cylinder means arranged at one end of the corresponding arc-extinguishing unit adjacent said movable contact and vent opening means arranged at the opposite end of the unit adjacent said relatively stationary contact to exhaust said blast of gas into said enclosure,

support beam means extending in said longitudinal direction within said enclosure,

a plurality of transverse partition plates extending perpendicularly to said longitudinal direction and secured to said support beam means at regular intervals to define a number of sections therebetween corresponding to the number of arc-extinguishing units,

control rod means extending in said enclosure parallelly to said longitudinal direction to actuate said

movable contact and said piston and cylinder means;
 said contact means and said puffer mechanisms of the arc-extinguishing units of odd rank being aligned along a first axis and said contact means and said puffer mechanisms of the arc-extinguishing units of even rank being aligned along a second axis, said axes extending parallelly to said longitudinal direction symmetrically with respect to the axis of said cylindrical enclosure, said transverse plates supporting said units in such a manner that in all sections but the first said vent opening means of the corresponding arc-

extinguishing unit is juxtaposed to said piston and cylinder means of the unit of next-higher rank so that said units overlap each other laterally thereby reducing the overall length of the assembled units of the pole.

5 2. A circuit interrupter according to claim 1, further comprising a plurality of voltage-dividing condensers inserted between said transverse plates.

10 3. A circuit interrupter according to claim 1, further comprising a plurality of series-connected resistor and auxiliary interrupter means inserted between said transverse plates.
